(57) **CLAIM**

The ornamental design for a play construction kit, as shown and described.

DESCRIPTION

FIG. 1 is a front, left, top perspective view of a first part of the kit for play construction assembly of the present invention;

FIG. 2 is the front elevational view of FIG. 1, the rear elevational view being a mirror image thereof;

FIG. 3 is the top elevational view of FIG. 1, the bottom elevational view being a mirror image thereof;

FIG. 4 is the left elevational view of FIG. 1, the right elevational view being a mirror image thereof;

FIG. 5 is a front, left, top perspective view of a second part of the kit for play construction assembly of the present invention;

FIG. 6 is the front elevational view of FIG. 5, the rear elevational view being a mirror image thereof;

FIG. 7 is the top elevational view of FIG. 5, the bottom elevational view being a mirror image thereof;

FIG. 8 is the left elevational view of FIG. 5, the right elevational view being a mirror image thereof;

FIG. 9 is a front, left, top perspective view of a third part of the kit for play construction assembly of the present invention;

FIG. 10 is the front elevational view of FIG. 9, the rear elevational view being a mirror image thereof;

FIG. 11 is the top elevational view of FIG. 9, the bottom elevational view being a mirror image thereof;

FIG. 12 is the left elevational view of FIG. 9, the right elevational view being a mirror image thereof;

FIG. 13 is a front, left, top perspective view of a fourth part of the kit for play construction assembly of the present invention;

FIG. 14 is the front elevational view of FIG. 13, the rear elevational view being a mirror image thereof;

FIG. 15 is the top elevational view of FIG. 13, the bottom elevational view being a mirror image thereof;

FIG. 16 is the left elevational view of FIG. 13, the right elevational view being a mirror image thereof;

FIG. 17 is a front, left, top perspective view of a fifth part of the kit for play construction assembly of the present invention;

FIG. 18 is the front elevational view of FIG. 17, the rear elevational view being a mirror image thereof;

FIG. 19 is the top elevational view of FIG. 17, the bottom elevational view being a mirror image thereof;

FIG. 20 is the left elevational view of FIG. 17, the right elevational view being a mirror image thereof;

(Continued)

FIG. 21 is a front, left, top perspective view of a sixth part of the kit for play construction assembly of the present invention;

FIG. 22 is the front elevational view of FIG. 21, the rear elevational view being a mirror image thereof;

FIG. 23 is the top elevational view of FIG. 21, the bottom elevational view being a mirror image thereof;

FIG. 24 is the left elevational view of FIG. 21, the right elevational view being a mirror image thereof;

FIG. 25 is a front, left, top perspective view of a seventh part of the kit for play construction assembly of the present invention;

FIG. 26 is the front elevational view of FIG. 25, the rear elevational view being a mirror image thereof;

FIG. 27 is the top elevational view of FIG. 25, the bottom elevational view being a mirror image thereof;

FIG. 28 is the left elevational view of FIG. 25, the right elevational view being a mirror image thereof;

FIG. 29 is a front, left, top perspective view of an eighth part of the kit for play construction assembly of the present invention;

FIG. 30 is the front elevational view of FIG. 29, the rear elevational view being a mirror image thereof;

FIG. 31 is the top elevational view of FIG. 29, the bottom elevational view being a mirror image thereof;

FIG. 32 is the left elevational view of FIG. 29, the right elevational view being a mirror image thereof;

FIG. 33 is a front, left, top perspective view of a ninth part of the kit for play construction assembly of the present invention;

FIG. 34 is the front elevational view of FIG. 33, the rear elevational view being a mirror image thereof;

FIG. 35 is the top elevational view of FIG. 33, the bottom elevational view being a mirror image thereof;

FIG. 36 is the left elevational view of FIG. 33, the right elevational view being a mirror image thereof; and,

FIG. 37 is a perspective view of the play construction kit showing all nine parts shown in FIGS. 1-36 in use.

The unshaded area of the block between the broken lines in FIGS. 13-16 represents unclaimed subject matter and forms

no part of the claimed design. The broken lines in FIG. 37 illustrate environmental subject matter and form no part of the claimed design.
